CONRAD HARRIS AND PAUL WILLIAM ZOINER, OF CINCINNATI,
OHIO.

Design No. 3,227, dated November 3, 1868.

DESIGN FOR A STOVE.

The Schedule referred to in these Letters Patent and making part of the same.

To all whom it may concern:

Be it known that we, CONRAD HARRIS and PAUL WILLIAM ZOINER, of Cincinnati, county of Hamilton, State of Ohio, have invented a new and useful Design for Cylinder Heating-Stoves for burning coal, to be known and called "The Rink;" and we do hereby declare that the following is a full and exact description thereof, reference being had to the accompanying photographs, and to letters of reference marked thereon, letter A showing a perspective view of the stove.

What we claim as our invention, and desire to secure by Letters Patent, is—

The design for cylinder heating-stoves, for burning coal, as shown and described.

C. HARRIS.
P. W. ZOINER.
